LENS-FORMING PROCESS.

1,312,920.

Specification of Letters Patent. Patented Aug. 12, 1919.

Application filed January 2, 1918. Serial No. 209,997.

To all whom it may concern:

Be it known that I, ARTHUR PELLOW, of Southbridge, in the county of Worcester and State of Massachusetts, have invented 5 certain new and useful Improvements in Lens-Forming Processes, of which the following is a specification.

This invention relates to improvements in processes of forming lenses and has particular reference to a novel and improved process of forming what is commonly known as 10 a fused bifocal lens.

One of the leading objects of the present invention is the provision of novel and improved process of forming fused bifocal lenses which shall entirely eliminate the necessity for metal, glass or other spacing members for holding the two parts of the 15 lens in spaced relation as they are submitted 20 to the fusing temperature.

A further object of the present invention is the provision of an improved construction of button or segment member for attachment to a suitably prepared major lens blank, which button shall be so formed and prepared with respect to the major blank as 25 to automatically space itself therefrom and allow but gradual contact between the joining faces of the two parts as they are subjected 30 to a feeding temperature.

Other objects and advantages of my improved process and structure for carrying the same into effect should be readily understood by reference to the following specification 35 taken in connection with the accompanying drawings, and it will be understood that I may make any modifications in the specific details of construction shown and described within the scope of the 40 appended claims without departing from or exceeding the spirit of my invention.

Figure I represents a plan view of the major blank.

Fig. II represents a similar view of the bifocal button.

Fig. III represents a transverse section with the parts in position for fusion.

Fig. IV represents a sectional view at right angles to Fig. III.

Fig. V represents a view similar to Fig. 50 III showing the article after fusion.

Fig. VI is a similar view taken at right angles to Fig. V.

In the drawings, the numeral 1 designates the usual major crown glass blank such as 55 ordinarily used in the formation of fused bifocals, having formed therein the spherical depression or countersink 2 adapted to receive and have united therewith the flint segment or button 3, the bifocal addition as 60 is well known being secured through the difference in index of refraction of the crown and flint glasses, and the exposed faces of the button and adjacent major blank being preferably subsequently ground off in a single 65 continuous curve, this subsequent process, however, not entering into the essentials of my present invention.

Hitherto in the formation of lenses of this character it has been deemed necessary 70 to hold the segment and major blank in spaced relation one to the other at one or more points, either by the interposition of a glass, metal or other wedge between the parts, by the formation of knobs or bosses on 75 the major blank engaging the segment to hold it in raised position, or by the use of means at the side of the major blank engaging a portion of the segment.

It is the purpose of my present invention 80 to do away with all these spacing members and to so construct the parts that they will initially satisfactorily space themselves.

In the accomplishment of this result, as should be clearly understood by reference 85 to Figs. III and IV, I grind the button 3 with a toric in place of a spherical curve but intended to eventually be fused in to a spherical countersink in the main blank.

For example, let it be supposed that the 90 curve of the countersink shown in Figs. III and IV is that of $a-7$. sphere; the curve of the segment illustrated in Fig. III might then, for example, be a slightly weaker contrageneric curve, such as $a+6$, so that when 95 the segment is placed on the major blank in the meridian of the $+6$. curve it will touch at the edges but the center portion will

be held slightly spaced from the bottom of the countersink.

In the opposite meridian, as shown in Fig. IV, for example, the curve on the countersink will be the same, while the curve on the button in this meridian will again be contrageneric to that of the countersink but will be a stronger curve, as for example $+8$, so that the countersink in this meridian will have a sharper curve than the countersink, and if touching in the center would curve upward away from the countersink at the edges. Touching at the center, however, is prevented on account of the fit in the opposite meridian, so that as shown in Fig. IV, the segment will be entirely spaced above the major blank in the meridian in question.

It will be understood that I have used the figures -7 , and $+6$, and $+8$, for purposes of illustration only, since the countersink may be formed with any desired curve, as may the toric surfaces of the segment, and I have found by experiment that satisfactory results may be obtained when there is only a quarter diopter variation between the curves of the countersink and segment in place of the full diopter here mentioned.

In any event, the essential result is the same, in that as the parts are subjected to a fusing heat the segment being of glass having a lower softening point than the major blank will soften as an entirety and on account of the center weight of the glass and the fact that it is supported at the ends only will first drop down from the weaker, or in the present case, the $+6$ curve to fit the slightly stronger or -7 curve, when there will then be a line of contact along the section of Fig. III, the production of this line of contact being, as before stated, due both to the weight of material at the center, with the end supports, and to the fact that at right angles to the line of Fig. III the segment on account of this stronger curve curves up away from the countersink. After the lens has thus settled down into its line of contact which steadies the segment, further heating action will continue the softening of the segment to such extent that its edges will then roll downward from the $+8$, to fit the -7 curve, this gradual dropping down of the edges in its rolling action from the center point serving to force out the air from the two glasses, preventing the formation of bubbles and allowing the two surfaces to properly unite.

To best bring out the effect produced in Fig. V the upper surface of the segment is shown concaved to bring out the effect of dropping of the structure shown in Fig. III, while in Fig. VI, the segment is shown as slightly convexed to bring out the effect

of rolling down of the edges into contact with the major blank in the opposite meridian. It will be understood, however, that the final effect produced on the outer surface of the segment is unimportant in this invention, since the upper face will be ground away, for example, substantially along the dotted lines shown in Figs. V and VI during the formation of the completed lens.

I claim:

1. The process of forming a fused bifocal lens, consisting in forming a major blank and segment with contrageneric surfaces, one of said surfaces being spherical and the other being toric, superimposing the parts to bring the surfaces in substantial contact one with the other, and subjecting the parts to a heat sufficient to cause one of the members to assume the shape of and unite with the other.

2. The process of forming a fused bifocal lens, consisting in forming a major blank with a concave spherical countersink, forming a segment with a convex toric surface, superimposing the segment on the countersunk portion of the major lens, whereby surface contact between the parts is prevented on account of the difference in curves of the segment in its two meridians, and subjecting the parts to a fusing heat to cause the segment to assume the curve of the countersink and firmly unite therewith.

3. The process of forming a fused bifocal lens, consisting in forming a major blank with a spherical countersink and a segment with a contrageneric toric surface one of whose curves is greater than and the other of whose curves is less than that of the countersink, placing the segment above the countersink and in contact with the major blank, and subjecting the parts to heating action to soften the segment till its curves will fit and correspond to the spherical curve of the countersink.

4. The process of forming a fused bifocal lens consisting in forming a major portion with a countersink and forming a segment with a toric face, one of the curves on the toric face being a stronger curve than the curve of the countersink or the curve in the meridian at right angles thereto on the segment, whereby as the blank is softened there will first be a line of contact between the segment and the countersink and the segment will subsequently roll down at both sides from the line of contact from the center outward in the final uniting of the parts.

5. The process of forming a lens of the character described, consisting in forming a major blank with a countersink and applying thereto a segment having a toric uniting face, its curve in at least one

meridian differing from that of the countersink to which it is applied, whereby the parts will first join in a line contact and the segment will subsequently roll out to assume the curvature of the countersink forcing all air bubbles out in advance of contact between the parts.

In testimony whereof I have affixed my signature, in presence of two witnesses.

ARTHUR PELLOW.
